UNITED STATES PATENT OFFICE

SAMUEL GOTTFRID SVENSSON, OF STOCKHOLM, SWEDEN

VACUUM CLEANER

Application filed December 18, 1929, Serial No. 414,944, and in Sweden December 31, 1928.

This invention relates to a device in vacuum cleaners and the like, and its object is to provide a vacuum cleaner which cleans the surface or object to be treated in an effective 5 way.

Another object of the invention is to provide a vacuum cleaner with an agitating device which is continuously rotated on account of the pressure difference between the 10 interior and exterior of the cleaner.

A further object of the invention is to provide a vacuum cleaner, in which the shaft of the agitating device is located nearer to one of the longitudinal edges or working 15 edges of the suction pipe than to the other.

Further advantages of the invention will, in addition to those new mentioned, be further mentioned in the following description, which referring to the accompanying drawings 20 sets forth two embodiments of the invention, said embodiments being taken as exemplifications. It is, however, clear, that these embodiments may be modified in many ways without giving up the principle of the 25 invention.

In the accompanying drawings Figure 1 is a diagrammatic view of a vacuum cleaner of any construction, said vacuum cleaner being provided with a device according to 30 the invention.

Figure 2 represents a vertical section, in detail, of the cleaning device, part of the box being broken away.

Figure 3 represents a vertical section, corresponding to Figure 2 showing a modified 35 form of box.

Figure 4 represents in detail a modification of the beating element shown in Figure 2.

Figure 5 represents a top plan view of the 40 cleaning device as a whole.

The vacuum cleaner is indicated by 1 and may be of any type as mentioned above. From the body of the cleaner runs the usual 45 suction pipe 2, which according to the invention is coupled to a cleaning device 3 consisting of a box having a plane lower side or bottom 4. The insertion opening for the suction pipe 2 is indicated by 5. In the working opening of this box there is located an agitating device, which is journalled in such

a way that it may be automatically brought to rotate during the operation on account of the pressure difference between the interior and the exterior of the cleaner.

In the embodiment shown in Figure 2 the 55 shaft 6 is provided with a number of beating elements 13, which may consist of a yielding material, for instance paper, pasteboard or the like. Moreover, the fore edges of the beating elements (counted in the direction of the 60 rotation) may be provided with reinforcing strips 14 or the like. This device is clearly shown in Figure 4 and the object of the same is to cause increased friction between the 65 beating elements and the object to be cleaned. 70 This embodiment is further characterized therein that one of the working edges, viz. 7, of the suction pipe or box 3 is located at a certain distance from the plane working surface or bottom 4 of the box 3, the turning 75 axis of the shaft 6 being located nearer to this edge 7 than to the other working edge 8. It thus results that the beating elements 13 will beat and drag against the object to be cleaned, and further that, the beating elements 75 on the side toward the working edge 8 extend relatively far from the revolving shaft.

The mode of operation of the device is as follows: When the vacuum cleaner is started, there is a reduction in pressure in the suction pipe or box 3, which results in the total pressure on the beating elements between the shaft 6 and the working edge 8 becoming considerably greater than the total 85 pressure on the beating elements between the shaft 6 and the edge 7. Thus, the shaft 6 will be rotated automatically in the direction of the arrow 12 (Figure 2). It is evident that the rotation of the agitating device results 90 in a beating of the carpet, or the like, being treated, and that thus a very effective cleaning action will result.

There is further shown in Figure 2, that the side walls 15 of the box or suction pipe 95 are extended from the working edge 8 towards the brush, so that they more or less cover the sides of the brush, as shown in Figure 3, these extensions may consist of separate parts 16, which are pivotally connected 100

to the side walls 15 by means of journals 17. The lower edge of these extensions may, moreover, run along a curved line diverging from the working surface or bottom 4, as shown at 18. By the extensions being formed in this way a certain resilience of the same is effected so that always an even and close resting against the object to be cleaned is gained.

- 10 In the embodiment according to Figure 2 the shaft is journalled with its journals 19 in the material of the suction pipe. The side walls of the box may for this purpose on one or on both sides be provided with slits or 15 guiding grooves 20 open towards the mouth of the suction pipe, the agitating device being held in position in the slits or grooves on account of the resilient pressure of the beating elements against the edge 7 located closer to 20 the journals 19.

Thus the agitating device may by reason of this arrangement be easily taken out or inserted in the box 3 by a single manipulation.

Having now described my invention, what 25 I claim as new and desire to secure by Letters Patent is:

1. In vacuum cleaners and the like, a suction pipe having a working opening, a rotary agitating means located in and substantially filling said opening, said agitating means having an axial shaft located nearer to one of the longitudinal edges of the working opening than to the other, and an operative portion of the agitating means extending 20 normally outside of the working opening of the suction pipe, whereby the agitating means may be automatically rotated during the operation of the cleaner on account of the pressure difference between the interior 25 and exterior of the cleaner.

2. A device according to claim 1, in which the agitating means includes beating elements mounted parallel to the axis, said elements extending at their points of attachment tangentially from their supporting body.

3. A device according to claim 1, in which the agitating means includes beating elements of resilient material mounted parallel 50 to the axis, said elements extending at their points of attachment tangentially from their supporting body and being provided with reinforcing strips adjacent their outer edges.

4. A device according to claim 1, in which 55 the bottom surface of the suction pipe is formed as a plane adapted to rest against the object to be cleaned, one edge of the working opening being located at a distance from said plane surface, and said agitating means being 60 mounted closer to said edge than to the plane surface.

5. A device according to claim 1, in which 65 the side walls of the device are extended beyond the edges of the working opening and adjacent the sides of the agitating means,

whereby they serve to cover the greater part of the sides of said means.

6. A device according to claim 1, in which the side walls of the device are extended beyond the edges of the working opening and adjacent the sides of the agitating means, whereby they serve to cover the greater part of the sides of said means, said side walls having their lower edges curved upward 75 from the lower edge of the working opening.

7. A device according to claim 1, in which the side walls of the device are extended beyond the edges of the working opening and adjacent the sides of the agitating means, whereby they serve to cover the greater part of the sides of said means, said side walls having their lower edges curved upward 80 from the lower edge of the working opening, said upwardly curved portions being formed as separate pieces pivotally secured to the side walls, whereby a continuous close contact with the material being cleaned is ensured.

In witness whereof I have hereunto signed my name.

SAMUEL GOTTFRID SVENSSON.
